UNITED STATES PATENT OFFICE.

WILHELM E. NAGEBORN, OF DETROIT, MICHIGAN, ASSIGNOR TO THE MONITOR BUTTON COMPANY, OF SAME PLACE.

BUTTON-DRILLING MACHINE.

SPECIFICATION forming part of Letters Patent No. 620,956, dated March 14, 1899.

Application filed April 13, 1898. Serial No. 677,403. (No model.)

To all whom it may concern:

Be it known that I, WILHELM E. NAGEBORN, a citizen of the United States, residing at Detroit, in the county of Wayne and State of Michigan, have invented certain new and useful Improvements in Button-Drilling Machines, of which the following is a specification, reference being had therein to the accompanying drawings.

10 My invention relates to multiple drilling-machines especially designed for drilling buttons; and it is the object of my invention to obtain a machine in which any desired number of holes may be drilled in the buttons 15 and in which a button is completed with each operation of the drills.

The invention consists in the peculiar construction of the carrier adapted to present the buttons successively to the different 20 drills; further, in the construction of the individual button-holding chucks of which said carrier is composed; further, in the means employed for opening said chucks to place a button therein and for automatically disengaging the completed buttons from their 25 chucks; further, in the means for operating and adjusting the positions of the drills, and, further, in the peculiar construction, arrangement, and combination of parts, as more 30 fully hereinafter described and claimed.

In the drawings, Figure 1 is a perspective view of my button-drilling machine. Fig. 2 is a sectional plan view thereof. Fig. 3 is a vertical longitudinal section on line xx , Fig. 35 2. Fig. 4 is a cross-section on line yy , Fig. 2. Fig. 5 is a bottom plan view of the bed. Fig. 6 is a perspective view of one of the chucks. Fig. 7 is a cross-section thereof. Fig. 8 is a perspective view of some of the 40 parts detached. Fig. 9 is a cross-section through a bearing for one of the drill-spindles. Fig. 10 is a plan thereof.

A is a table or bed, in the upper face of which is formed a rectangular annular groove 45 or channel B around a central panel C.

D are a series of chuck-blocks which are of rectangular form and of a diameter equal to the width of the channel B. These blocks are slidingly secured in the said channel, the 50 lengths of the sides of which are exact multiples of the diameter of the blocks, the depth

of said channel being also approximately the same as the thickness of said blocks.

Each chuck-block is provided with plates or jaws a a' , which are slidably secured upon the upper face of the block, preferably in the undercut guides or slideways b thereon, and each jaw is provided with a V-shaped notch c , which notches together form a recess at the center of the chuck-block above a smaller aperture d , passing through said block. The outer edges of the plates a and a' are oppositely inclined or wedge-shaped, and e is a plate having the bifurcated wedge-shaped arms f , adapted to embrace the plates a and a' and bear against the inclined edges thereof. The plate e is secured in undercut or dovetailed guides or slideways g , arranged at right angles to the slideways b .

h are pins extending downward from the under side of the plate e into slot i in the blocks, arranged parallel to the guides g . These slots communicate with the recesses j in the blocks, in which are placed the springs k , bearing at one end against the screw-threaded plugs l and at their opposite ends against the sliding blocks m , which bear against the pins h , the arrangement being such that the springs k will hold the plate e normally into position, where it will wedge the two sliding jaw-plates a and a' together. The meeting edges at the outer ends of the plates a and a' are cut away to form a V-shaped notch u , and the opposite edge of the block D has formed therein the V-shaped notch o . The corners of the blocks are preferably rounded slightly, as shown.

The chuck-blocks D are placed in the groove B so as to have the notch u toward the front and the notch o toward the rear of the bed, and the number of the blocks is two less than that required to completely fill the channel B—i. e., so as to leave the diagonally opposite corners vacant.

E, E', E², and E³ are pusher-arms for the 95 blocks D, arranged, respectively, at the four corners of the channel B and normally withdrawn into recesses F in the sides of said channel. These arms are adapted to be reciprocated to push along the row of blocks in 100 each side of the channel B, the diagonally opposite arms operating simultaneously and

alternately with the other diagonally opposite pair. These arms pass downward through slots F' in the bottom of the channel and are connected with suitable mechanism on the 5 under side of the machine for reciprocating them in the manner above described. This mechanism, as shown in the drawings, comprises the bars G, G', G², and G³, slidably secured in bearings on the under side of the 10 bed and to which the pusher-arms are secured.

H is a rotary head journaled centrally on the under side of the bed and provided with the arms H' and H².

I and I' are arms or projections secured to 15 the sliding bars G' and G², respectively, and with which the arms H' and H² are respectively adapted to engage in the rotation of the head H to slide said bars in one direction in their bearings.

20 J and J' are levers having their opposite ends connected, respectively, to the bars G' G², and G G³, said levers being adapted in the movement of the bars G' and G² to impart an opposite movement to the bars G³ and G. These levers are pivoted on the under side of the bed, the lever J being preferably fulcrumed on the spindle of the head H and the ends of both levers being slotted to slid- 25 ingly engage with pins on the bars.

30 I² is a lever, one end of which is connected to the bar G' and the opposite end extending into the path of the arm H² on the head H.

I³ is an arm on the lever J', which also extends into the path of the arm H², said arm 35 I³ and lever I² being adapted to impart a reverse movement to the bars from that imparted thereto by the engagement of the arms H' and H² with the arms I and I', respectively.

K is a drive-shaft extending longitudinally 40 and centrally below the bed and journaled in bearings at the opposite ends of said bed.

K' and K² are miter-gears connecting the shaft K with the head H.

K³ is a cam at one end of the shaft K.

45 L is a rock-shaft extending longitudinally near the rear side of the bed and journaled in bearings thereon.

L' is a rock-arm on said shaft, extending down into proximity to cam K³.

50 M is a bar extending along the rear edge of the bed, to which is secured a series of fingers M', adapted to slidingly engage with slots in the bed extending into the channel B. These fingers are arranged to be opposite the centers of the chuck-blocks in the rear side of the channel B and are V-shaped at their inner ends to engage with the V-shaped notches 55 o in said chuck-blocks.

M² are springs tending to force said fingers 60 inward.

L² and L³ are rock-arms on the rock-shaft L, adapted to bear against the ends to force said bar outward and disengage the fingers from the chuck-blocks.

65 N is a supporting-frame for the drill-spindles, comprising the end posts N' and the horizontal bar or plate extending longitudinally

above the rear row of clutch-blocks in the channel B.

O are the drill-spindles, vertically slidingly 70 secured in bearings O', secured to the frame N centrally above each of the chuck-blocks. The bearings O' are provided with a limited lateral adjustment by means of screws O², engaging with slots in flanges O³, resting on 75 the frame N.

O⁴ are pinions on the spindles O, which are connected to each other by intermediate pinions O⁵, one of which is mounted upon the drive-spindle O⁶. These pinions are journaled on stub-axes, which are also capable of lateral adjustment on the frame N.

P is a vertically-sliding frame having the laterally-extending arms P' adjustably secured thereto and forked or slotted at their 85 outer ends to engage with grooved collars O⁷ on the spindles O.

P² are springs sleeved upon the vertical members of the frame P and tending to hold 90 said frame in its raised position.

Q is a rock-shaft journaled in bearings below the bed and having the rock-arm Q', adapted to engage with the cross-bar P³ on the frame P, and the actuating rock-arm Q², engaging with a cam K⁴ on the shaft K. 95

At the forward edge of the bed is arranged a sliding plate R, having the projecting points r, adapted to engage with the V-shaped notches u of two of the chucks. This plate is also provided with the projections s, adapted to strike against the bifurcated ends f of the sliding plates e of said chucks.

S is a rock-shaft journaled in bearings on the forward side of the bed and having the rock-arms S', adapted to bear against the 105 plate R.

S² is a rock-arm on one end of the shaft S, extending into engagement with a cam K⁵ on the shaft K.

T is a pin vertically slidingly secured in an 110 aperture in the bed below the channel B and at a point to be in registration with the central aperture d of the chuck-blocks when in the position indicated by the letter X, Fig. 2. This pin is secured to the plate or head T' below the bed, which is adapted to be raised by the rocking of the pivotal arm or lever T², so as to project the pin upward through the aperture d of the chuck-block. The arm of lever T² is operated by the arm H' on the head 120 H, which in the rotation of said head comes into contact with the end T³ of said lever, depressing said end and raising the opposite end, which contacts with the under side of the plate T' and raises it. To hold the plate in 125 its raised position temporarily after the arm H' has disengaged from the lever T², a latch-arm S³ is provided, adapted to catch under said plate and having an engagement with the rock-arm S', by means of which it is subsequently tripped in rocking said arm.

U is an arm secured to a vertical rock-shaft U' at one edge of the bed, adapted to sweep over the top of the bed and having a notched

end U^2 , which passes over the center of the chuck in the position indicated by the letter X.

U^3 is a slotted actuating-arm for the arm U, arranged below the bed and engaging with 5 a pin on the reciprocating bar G^3 .

The parts being constructed and arranged as shown and described, the operation of the machine is as follows: Motion communicated to the shaft K will cause the cam K^5 thereon 10 to actuate the arm S^2 , which will rock the shaft S and arm S' thereon, causing the latter to press against the plate R and slide said plate in its guides. This will cause the projections s to press against and move back- 15 ward the wedge-arms f of the plates e on the two adjacent chuck-blocks at the position marked X and Y, Fig. 2. At the same time the points r on the plate will enter the notches u of said chucks and spread the jaws a a' 20 thereof apart. The operator now places a button-blank in the recess formed by the notches in the jaws of that chuck at the position marked Y. The further movement of the shaft K will release the pressure of the 25 rock-arm S on the plate R and allow the retracting-springs S' for said plate to withdraw the points r and projections s from their engagement with the chucks, upon which the spring j will press forward the wedge-plates 30 and close the jaws a and a'. In the meantime the movement of the rotary head H, caused by the miter-gears K' and K^2 , will bring the arm H^2 into engagement with the arm or lug I' on the sliding bar G^2 , Fig. 5, moving said 35 arm toward the right and through the connecting-lever J' imparting a reverse movement to the bar G. The movement of the bars will cause their corresponding pushers E² and E to push the rear and front rows of 40 chuck-blocks respectively toward the right and the left, Fig. 2, filling the previously-vacant diagonally-opposite corners Z' and Z² and leaving vacant the corners Z and Z². Another chuck-block is thus brought into the 45 position Y, which will have its jaws spread to receive a button-blank in the manner before described. The arm H^2 after disengaging from the arm I' will next come into engagement with the arm I³ on the lever J', which 50 will cause a reverse movement of said lever and the bars G G², carrying the pushers E and E² back to their original positions in the recesses F. The arm H^2 will then come in contact with the arm or projection I on the 55 sliding bar G', moving that bar and through the connecting-lever J simultaneously reversely moving the bar G³, so as to cause their respective pushers E' and E³ to move the said rows of chuck-blocks, the row on the left- 60 hand side, Fig. 2, being moved toward the rear and that on the right-hand side toward the front of the bed. This set of sliding bars and pushers are returned by the arm H^2 striking the inner end of the lever I², after 65 which the arm H^2 again comes into engagement with the arm I', and the operation is repeated. Each revolution of the head H

will thus feed the entire series or chain of chucks forward by the space of one chuck, and when the chucks having the blocks engaged therewith arrive at the rear side of the channel they will hold the blanks in operative relation to the drills. Rotary motion is then imparted to these drills through a suitable belt connection to a pulley O⁸ on the 70 spindle O⁶ and from the latter through the pinions O⁵ and O⁴ to each of the drill-spindles O, which are provided with suitable chucks at their lower ends for holding the drills. In the drawings I have shown five of these 75 drill-spindles, as that is the largest number of holes generally formed in a button; but any number of spindles may be employed, and when the machine is used for buttons requiring a lesser number of holes the extra spindles may be thrown out of operation by removing the intermediate pinions O⁵, or they may be left in operation and the drills only removed. During the interval in which the 80 chucks C are at rest the cam K⁴ on the shaft K will rock the arm Q² on the rock-shaft Q and cause the rock-arms Q' on said shaft to depress the bar P³ of the vertically-sliding frame P, carrying said frame downward and causing the arms P', engaging with the 85 grooved collars O⁷, to carry down the spindles O, pressing the drills through the button-blanks in the chucks below. The position of these drill-spindles in relation to the centers of the button-chucks beneath is such that 90 each will bore a hole at a different point in the button, and in order that the position of these holes may be precisely the same in each button I provide means for holding all the chucks beneath the drill-spindles during the 95 time of drilling. This is accomplished by the fingers M', having the V-shaped ends, which are moved inward by the springs M² bearing against the bar M and engaging said fingers with the V-shaped notches o in the chuck-blocks. After the drilling is performed, but 100 before the chuck-chain is again set in motion, the cam K³ will rock the arm L', rock-shaft L, and rock-arms L², causing the latter to push back the bar M and withdraw the fingers M' 105 into their slots in the bed. Just before completing the circuit each of the chuck-blocks will be brought into the position X, Fig. 2, when in the rotation of the head H the arm H' thereon will rock the lever T², causing it 110 to lift the plate T' and force the pin I upward through the aperture d in the chuck. This will lift the finished button above the jaws a and a' of the chuck, which jaws have been 115 previously spread by the operation of the projections s and points r on the plate R, and hold the button in this position until the arm or sweep U is swung around and carries it 120 over the edge of the bed, dropping it into the hopper V. 125

Although I have shown and described a machine as employed for drilling the buttons, it is obvious that the same mechanism might be employed in connection with other forms of

tools—such, for instance, as the facing-tools. I have also described the chuck-blocks as of rectangular shape and traveling in a rectangular groove in the bed; but this may be varied by forming the groove of any polygonal shape, provided that the chuck-blocks are of a similar polygonal form.

What I claim as my invention is—

1. In a button-machine, the combination 10 with the tool of a carrier for the blanks comprising a series of independent chuck-blocks a support therefor and means for intermittently moving said blocks in an endless path to and from said tool upon said support.
- 15 2. In a button-machine the combination with the tool, of a bed or table provided with an endless guideway, a series of chuck-blocks slidingly engaging with said guideway, means for intermittently moving said blocks to and 20 from said tool and means for causing the tool to operate on the work and for opening the chucks to engage and disengage the work at one point of the way.
- 25 3. In a button-machine, the combination of a table or bed having a polygonal guideway, a series of chuck-blocks slidingly engaging with said guideway, there being a blank space equal to a chuck left at one corner of the way, means for successively feeding the series of 30 blocks on each side of the way toward the vacant space at the corner.
- 35 4. In a button-machine, the combination of a table or bed having a parallelogrammic guideway, a series of chuck-blocks slidingly engaging with said guideway being two less than enough to fill said way so as to leave blank spaces at diagonally opposite corners, means for moving the series of blocks on each side of the way, the parallel series being moved 40 simultaneously in opposite directions and alternately with the series at an angle thereto.
- 45 5. In a button-machine the combination of a table or bed having a polygonal endless channel formed therein, a series of chuck-blocks of similar polygonal shape slidingly engaging with said channel, there being a vacant space left at one corner of said channel and means for successively feeding the series of blocks in each side of the channel toward 50 the vacant corner, comprising pushers arranged at each corner normally withdrawn into a recess in the bed and adapted to be projected to push their corresponding series and to be withdrawn again into their recesses.
- 55 6. In a button-machine, the combination of the bed or table having an endless channel formed therein, a series of chuck-blocks for holding the blank, slidingly engaging with said channel, means for intermittently feeding said blocks in said channel and means for locking a portion of said blocks during the interval of rest and simultaneously causing the tool or tools to work upon the blanks held by said locked chuck-blocks.
- 65 7. In a button-machine, the combination with the tool, and a table or bed having a polygonal endless channel formed therein, of

a series of chuck-blocks of similar polygonal shape slidingly engaging with said channel, each block having a V-shaped notch on one side, a finger having a V-point slidingly secured in a recess in the bed on that side of the channel corresponding to the notched sides of said blocks, means for projecting said finger to lock the registering block during 75 the interval of rest, and for simultaneously causing the tool to operate on the work held by said block.

8. In a button-machine, a chuck-block comprising the block, a jaw-plate slidingly secured to said block and a wedge-plate cross-slidingly secured to the block and adapted in the movement to force said jaw to its closed position.

9. In a button-machine, a chuck-block comprising the block, jaw-plates slidingly secured to said block and a bifurcated wedge-plate cross-slidingly secured to said block and embracing said jaws adapted in its movement to force said jaws toward each other. 85

10. In a button-machine, a chuck-block comprising the block, jaw-plates slidingly secured to said block, a bifurcated wedge-plate cross-slidingly secured to said block and embracing said jaws, a spring in a slotted recess in said 95 block, and a pin on said wedge-plate projecting through said slot and engaging with said spring, substantially as described.

11. In a button-machine, the chuck-block C having the slideways *b* and *g* arranged at right angles to each other and the slotted recesses *j*, the jaw-plates *a* and *a'*, and the bifurcated wedge-plate *e* slidingly secured in the ways *b* and *g* respectively, the wedge-plate embracing the jaws, the pins *h* on said wedge-plate 105 projecting into the slotted recess *j*, the springs *k* in said recesses and the blocks *m* and plugs *l* all arranged substantially as described.

12. In a button-machine, the combination with the bed, having an endless channel 110 formed therein, of a series of chuck-blocks slidingly engaging with said channel, each comprising the block, jaw-plates and a bifurcated wedge-plate cross-slidingly secured to said block and a spring for holding said wedge-plate 115 in a position to clamp the jaws, and a sliding plate or head at one point of the bed adapted to be moved to push back said wedge-plate and having a wedge-point adapted to separate said jaws. 120

13. In a button-machine, the combination with the bed, having an endless channel formed therein, of a series of centrally-apertured chuck-blocks slidingly engaging with said channel and adapted to be intermittently 125 fed thereon, a pin in a recess in the bottom of said channel adapted to be projected upward through said central aperture of the registering chuck during its interval of rest and means for simultaneously opening the 130 jaws of said chuck.

14. In a button-machine, the combination with the bed having an endless channel formed therein of a series of chuck-blocks slid-

ingly engaging with said channel and adapted to be intermittently fed therein, each chuck-block comprising a centrally-apertured block, slidily secured thereon and a spring-pressed sliding wedge-plate for closing said jaws; a pin in a recess in the bottom of said channel, adapted to be projected upward through the central aperture of the registering chuck-block during its interval of rest, a slide on the bed for pressing back the wedge-block and spreading the jaws of said chuck-block, and a sweep for the purpose described.

15. The combination with the bed having an endless channel formed therein and a series of chuck-blocks slidily secured and intermittently fed in said channel, each comprising a centrally-apertured block, jaws slidily secured thereon and a spring-pressed wedge-plate for closing said jaws; of the slide

20. R having the bearings s and points r adapted to press back the wedge-plate of two adjacent chucks and spread the jaws thereof, a pin in a recess in the bottom of the channel adapted

to be projected upward through the central aperture of one chuck and the sweep U for 25 the purpose described.

16. In a button-drilling machine, the combination with the bed having an endless channel formed therein and a series of chuck-blocks slidily engaging and intermittently fed in said channel, of a plurality of drill-spindles, having pinions thereon above said chucks, adjustable bearings in which said spindles are vertically slidily journaled, a driven shaft and intermediate pinions for rotating said spindles and a vertically-reciprocating frame having forked arms engaging grooved collars on said spindles for lowering and raising the same.

30. In testimony whereof I affix my signature 35 in presence of two witnesses.

WILHELM E. NAGEBORN.
